UNITED STATES PATENT OFFICE.

PATRICK H. QUINN, OF LOS ANGELES, CALIFORNIA.

GAME.

Application filed November 12, 1924. Serial No. 749,440.

An object of this invention is to provide a game that is interesting and instructive and which can be manufactured and sold at a low cost.

5 An object of the invention is to provide a game that is especially adapted to impress upon the minds of children the danger and hazard of street crossing, so that in real life they will approach a crossing with a full 10 knowledge of the danger and hazard pertaining thereto; so that they will be careful and cautious in crossing in front of street cars and automobiles.

An object of the invention is to provide 15 an instructive game that is easy to learn and play so that very small children of a kindergarten age can play it.

Another object is to provide an educational game comprising a board and associated parts that are strongly constructed.

Other objects, advantages and features of invention may appear from the accompanying drawing, the subjoined detailed description and the appended claims.

25 The accompanying drawing illustrates the invention.

Figure 1 is an edge view of a game constructed in accordance with this invention showing a board with small dummy street 30 cars, automobiles and pedestrians arranged thereon in position to play a game.

Fig. 2 is a plan view of the board and associated parts as arranged in Fig. 1, showing a preferred coloring of the movable parts; and also of the green lawns at 35 the corners of the board.

Fig. 3 is a fragmental section on line x^3 , Fig. 2.

Fig. 4 is an enlarged fragmental perspective view of the top of the stand showing the arrangement of the recesses in the rim thereof.

Fig. 5 is an enlarged fragmental perspective view of the bottom end of the stem, 45 showing a protrusion that is adapted to be seated in a recess of the stand when the stem is at rest.

Fig. 6 is a fragmental section of the stem and protrusion or roller, on line x^6 , Fig. 5.

50 The board 1 has a street crossing indicated on its top surface that comprises a sidewalk having starting points 2, 3, 4, 5, and finishing points 2', 3', 4', 5'; driveways for automobiles having starting points 6, 7, 55 8, 9 and finishing points 6', 7', 8', 9', and

double track street railroad crossings having starting points 10, 11, 12, 13 and terminal points 10', 11', 12' and 13', respectively.

Adjacent the intersection of the streets 60 are four starting and finishing lines 14, 15 that are arranged across the streets so as to form a hollow square that is sub-divided into a number of small squares 16 of equal dimension; that form spaces on which the 65 dummy street cars c , automobiles a and pedestrians b can be moved as by shifting them from square to square so that they are made to travel from the starting lines to the finishing lines. 70

The street approaches to the starting and finishing lines 14, 15 or to the squares 16 are sub-divided into elongated rectangles 17 that are equal in width to the sides of the squares 16 and they form spaces on which the 75 dummy automobiles a and street cars c rest at start and finish of the game.

The spaces 2, 3, 4 and 5 and 2', 3', 4' and 5' representing the sidewalks form elongated rectangles similar to the rectangles 80 17 and provide spaces on which the dummy pedestrians rest at start and finish of the game.

Each player is preferably provided with 85 two street cars c , two automobiles a and three pedestrians b . It is understood, however, that this number of movable objects can be increased or decreased as may be desired; and also that the number of players can be two, three or four. 90

The dummy cars, automobiles and pedestrians are preferably colored so as to be readily distinguished apart. As shown in Fig. 2 the movable objects are arranged so that four players A, B, C and D can play a 95 game, and preferably A's cars, automobiles and pedestrians are colored red: B's black, C's green and D's yellow and at the start of the game they are arranged in their appropriate and respective starting places as 100 shown.

In the center of the board 1 a hollow stand 18 is fastened so that its rim 19 will stand a considerable distance above the top surface of the board. The stand 18 is provided with a bead 18' which forms a shoulder adapted to engage the top surface of the board and the lower end of said stand 18 is buried over to clamp the stand in an upright position in the board 1, that is to say 110

the board is clamped between the bead 18' and the burred over lower end of the stand 18.

A dummy traffic officer or indicator 20 is provided with a stem 21 that is adapted to extend into and revolve in the hollow stand 18. A protrusion in the form of a roller 22 is journaled on a pin 22' which is secured to said stem 21 by any well known means, 10 as by riveting. The roller 22 is adapted to engage the rim 19 of the stand 18 and when the pedestal is at rest said roller is adapted to be normally seated in recesses 23 formed in the rim 19. The dummy officer 20 preferably has his arms extended from his sides 15 as is customary in indicating the direction in which traffic is to travel.

The recesses 23 are so arranged in the rim of the stand 18 which in turn is so arranged 20 relative to the board 1 that when the roller 22 on the stem 21 comes to rest in one of said recesses the arms of the traffic officer will point centrally through one or the other of the cross streets; and when so pointing 25 indicates the player or players that are to play. That is to say, the traffic officer is spun by one of the players to determine who is first to play and if a hand of the officer points to the spinner it is his first play, and 30 the player toward which the other hand points plays second, but if the hand of the officer does not point to the spinner then the first play goes to the player to the right of the spinner and the second play to the 35 player opposite him.

Each player must in the order above indicated then move or advance their movable objects a total of four spaces unless prevented from so doing by a blockade. The 40 four spaces may be made by one object or divided up among the several objects, except that a move of at least one square must be made by a street car if possible. The moves may be from a rectangle to a square or from square to square, or from a square to a rectangle as the case may be.

The officer is then spun by the player on the right of the player last spinning and the 45 plays proceed as above to the end of the game.

The street cars are movable forward in straight courses on their respective tracks, and may be moved one to four spaces each time they are played or moved. Although 50 a street car occupies two squares on the board a move is made by advancing it one square or space 16.

In other words assuming that player A advances a street car on track 10 until it occupies a rectangular space inside of the B- 55 finish line, then the movement of that street car is finished and counts for A at the conclusion of the game. The street cars of all the players are moved in a similar manner 60 on their respective tracks; it being under-

stood of course that a player can move his street cars in any order in which the plays can be made, either close together or far apart as may best suit a player.

The automobiles *a* can be moved from the 70 rectangles to the squares and from square to square in advancing and sidewise courses so as to consummate a forward trip across the street or to consummate a left hand turn around the traffic officer or to consummate 75 a right hand turn; but they cannot be moved backwards. Also they can make right and left hand turns to go around one another or other movable objects.

The pedestrians can be moved across the 80 street intersection from square to square in an advancing direction along the squares immediately in front of the start and finish lines, but they cannot be moved backward or 85 sidewise from the course initially started, except that when a pedestrian has been moved fully across a street crossing it can be turned at right angles to continue its 90 course and again cross the street. In other words the pedestrians of player A must first 95 pass from the sidewalk 2 to sidewalk 3', or to sidewalk 5 crossing the street directly in front of the starting line of the street cars and automobiles of player C or A and in front of the finishing line of player D or B. Then the pedestrians of A may be turned at right angles and cross from the sidewalk 3' or 5 to the sidewalk 3 in front of the starting line of the street cars and automobiles of player B or D and in front of the 100 finishing line of player A or C as the case may be. The pedestrians of the other players are moved in a similar manner.

The rules of the game may be varied to suit different occasions but it has been found that the game may be satisfactorily played 105 in accordance with the following rules:

At the start of the game it is preferable to require each contestant to move four pieces on his first play and afterwards the moves may be divided up among the several objects but moving a street car in each play if possible.

No space may be occupied by more than 110 one pawn or object at the same time.

An automobile or pedestrian is forfeited when it is caught in the traffic, i. e., when an automobile or pedestrian occupies a square across which a street car by traffic signal is entitled to move, it is forfeited to the player moving onto or past the square occupied by the automobile or pedestrian, and scores for the player taking or running over the same.

Street cars cannot take street cars, automobiles cannot take automobiles and pedestrians cannot take pedestrians.

Street cars can take automobiles and pedestrians and automobiles can take pedestrians.

The street cars must move on their respec-

tive tracks only and finishes its travel when across its finish line.

Autos must move in the two rows of squares to the right of the car tracks and 5 must not travel along the tracks nor along the pedestrian's path.

A pedestrian may pass an opponent's pedestrian in the same square.

Autos may make right or left turns, go 10 straight across or make a complete turn with varying scores. Autos may pass other autos on the left side and each side movement of one square counts as one move.

The game is finished when any one player 15 has moved all of his objects across the board to a counting station or if a blockade makes further moves impossible. The player having the greatest number of points wins the game.

20 The points may be determined in the following manner:

For each street car that crosses the street 25 a value of twenty points is given. For each automobile completing a right turn no score is given. For each automobile crossing the street straight ahead a value of twenty points is given. For each automobile completing a left turn a value of thirty points is given. For each automobile making a complete turn around the traffic officer and finishing at the finish line, which is a continuation of its starting point, a value of forty points is given. For each automobile 30 forfeited a value of forty points is given to the person taking the same. For each pedestrian crossing one street a value of ten points is given. For each pedestrian crossing two streets a value of twenty points is given. For each pedestrian forfeited a 35 value of twenty points is given to the person taking the same.

The indicator 40 is free at front and back from indicating arms and the indicating arms are on opposite sides of the center of rotation of the indicator, that is, the indicator has only two indicating arms and these arms are in a common plane so that a child 45 of kindergarten age, and able to read, can play the game without confusion and by 50 making the indicator in the form of an

officer with arms outstretched, the child of tender years will be more readily brought to associate with the game, the actual conditions on the street.

I claim:

1. The game set forth comprising a board having a street crossing indicated thereon that is sub-divided into squares; a stand extending up from said board and having recesses therein; a revolvable dummy traffic 60 officer on said stand that has its arms and hands extended sidewise; means for stopping said officer from rotations so that the hands point centrally through one or the other of the crossed streets; and dummy 65 street cars, automobiles, and pedestrians adapted to be moved on said board to play a game around said officer.

2. The game set forth comprising a board having a street crossing indicated thereon that is sub-divided into rectangles and squares; a double track railroad crossing indicated on said board; dummy street cars movable on said track; dummy automobiles adapted to be moved on the rectangles and 70 squares of said street crossings; a dummy pedestrian adapted to be moved along certain squares of said street crossing; and revolvable means for indicating on which 75 streets the traffic of street cars, automobiles 80 and pedestrians are to move.

3. The game set forth comprising a board having a street crossing indicated thereon; four sets of movable objects adapted to be arranged and moved on said board each set 85 of a different color and comprising street cars, automobiles and pedestrians; and a revolvable traffic indicator in the center of said board.

4. A game of the character set forth comprising a board having a street crossing indicated thereon; movable objects for each player adapted to represent street cars, automobiles, and pedestrians; and means to indicate which of said players are to move 90 their respective objects.

In testimony whereof, I have hereunto set my hand at Los Angeles, California, this 5th day of November, 1924.

PATRICK H. QUINN.
